UNITED STATES PATENT OFFICE.

LOUIS W. G. FLYNT, OF ROCHESTER, NEW YORK, ASSIGNOR TO UNITED SHOE MACHINERY COMPANY, OF PATERSON, NEW JERSEY, A CORPORATION OF NEW JERSEY.

CEMENTING-MACHINE.

1,163,651.

Specification of Letters Patent Patented Dec. 14, 1915.

Application filed September 28, 1910. Serial No. 584,242.

To all whom it may concern:

Be it known that I, LOUIS W. G. FLYNT, a subject of the King of Great Britain, and residing at Rochester, in the county of Monroe and State of New York, have invented 5 certain Improvements in Cementing-Machines, of which the following description, in connection with the accompanying drawings, is a specification, like reference characters 10 acting on the drawings indicating like parts in the several figures.

This invention relates to machines for delivering liquid material to stock and is herein illustrated as embodied in a machine 15 for applying cement to the skived margin of a piece of leather preparatory to the folding operation.

The effect of skiving or splitting a piece 20 of leather is to a certain extent to raise the fiber and to expose the pores. When a coating of cement is applied to such a surface in the usual manner, for example by a brush or a roll, such coating may often be easily peeled off owing to the fact that the cement 25 has not been worked into the pores and raised fibers of the leather. The coating, in short, seems not to adhere with sufficient firmness.

Accordingly, one feature of the present 30 invention consists in the provision of means for applying cement under pressure to a piece of stock and means for rubbing into the stock the cement so applied. By thus forcibly squirting the cement upon the stock 35 and then rubbing it in a thorough impregnation is obtained so that the coating of cement will cling tenaciously. Any suitable means for accomplishing this result may be employed; and in the illustrated embodiment 40 of the invention, in order to simplify the machine and to obviate the necessity for providing two separate mechanisms for squirting the cement and for rubbing it into the stock respectively, the nozzle through 45 which the cement is forced is controlled by a valve which has fast thereto a wiper or rubbing member provided with passages located at one side of the center thereof so that when the valve is opened the cement is 50 squirted upon the stock in advance of the portion engaged by the wiper or rubbing

member. And in order to increase the efficiency of the machine another feature of the invention consists in means for feeding forward a piece of stock and automatic means 55 for squirting cement upon stock so fed. In the illustrated embodiment the wiper referred to above projects from the nozzle and, as it is moved upwardly by the piece of stock, communicates movement to the valve 60 and thereby permits the cement to be forced out upon the stock.

It is desirable that the cement to be delivered be kept under pressure constantly 65 and that this pressure should be approximately uniform.

Accordingly, another feature of this invention consists in the provision with a receptacle for cement, said receptacle being provided with an outlet, of means acting 70 through friction with the cement for causing said cement to accumulate under pressure at said outlet. In the illustrated embodiment a cylindrical receptacle for cement contains rotatably mounted therein a 75 plurality of thin disks having a common axis which coincides with the axis of the receptacle; and a deflector having fingers of a width equal approximately to the width of the spaces between the disks extends from a 80 point near the outlet to the hub on which the disks are mounted. The surface exposed to the cement by these disks is greater than the surface of the interior of the receptacle so that by rotating the disks a force 85 is frictionally applied to the cement which moves it in the direction of rotation of the disks. This movement, however, is opposed by the deflector, the result being that a body of cement under pressure is maintained 90 near the outlet. With this construction the cement to be delivered to the stock is kept under an approximately constant pressure which, since it is frictionally applied, can at no time become excessive.

These and other features of the invention including certain details of construction and combinations of parts will be described in connection with the accompanying drawings and pointed out in the appended claims.

Referring to the accompanying drawings:—Figure 1 is a side elevation of a ma-

chine in which the present invention is embodied; Fig. 2 is an end elevation, the cover of the cement receptacle having been removed; Fig. 3 is a plan showing the stripper or deflector; Fig. 4 is a detail sectional view of the nozzle, the combined valve and wiper being shown in full lines; Fig. 5 is a view of the lower portion of the nozzle taken at right angles to Fig. 4; and Fig. 6 is a plan of the nozzle and its associated parts.

Fastened to the frame 1 by bolts 3 is a bracket 5 which has formed integral therewith a cylindrical feed box or receptacle 7, and to this receptacle a cover 6 is attached by means of bolts 9. A rotatable shaft 11 mounted in bearings 13 and 15 formed respectively in a boss on the frame and in a boss on the feed box carries at one end a driving pulley 17 and at the other end a plurality of feed disks 19 which are spaced apart by collars 20. A stripper or deflector 21 held in place by one of the bolts 9 has fingers 23 separated by slits 25, and this stripper is held in the position shown in Fig. 2, the feed disks 19 extending into the slits 25 and the fingers 23 substantially filling the spaces between the disks. The extent of surface exposed to the cement by the disks 19 is much greater than the extent of the interior surface of the receptacle. Consequently when the disks 19 are rotated, the cement is moved in their direction of rotation. This movement, however, is opposed by the stripper 21 with the result that cement accumulates under pressure in the lower part of the receptacle 7.

Extending from the lower part of the receptacle 7 and communicating with the interior thereof is a threaded pipe 27 to which is attached by means of a hollow nut 29 a feed tube or nozzle 31 provided at its lower end with a conical valve seat 33 which terminates in an elongated slot 35. Adapted to cooperate with this seat is a valve 37 provided with an elongated rubber or wiper 39, said wiper being provided with passages or grooves 41 through which when the valve is raised, cement is forced out upon the stock. These grooves or passages 41 are located on that side of the nozzle from which the stock is presented so that the cement is delivered to the stock in advance of that portion which is engaged by the wiper. The valve 37 has two curved portions 43 which cross piece 49 carried by the nozzle 31; and two flat cut-away portions 45 which permit the cement to reach the passages 41 when the valve is raised. Fast to the valve is a stem 47 the upper end of which passes through a cross piece 49 carried by the nozzle 31; and a spring 51 bears at one end against this cross piece and at the other end against the valve 37. With the construction thus far

described and with the understanding that cement is supplied to the receptacle 7 from any convenient source as, for example, through a pipe 53, rotation of the shaft 11 in a clockwise direction, as viewed in Fig. 2, causes cement to be delivered to the nozzle 31 under pressure. If now a piece of stock is held against the wiper 39 and moved along beneath the nozzle, cement will be applied to the stock under pressure through the passages 41 and will then be rubbed into the stock by the wiper 39.

The mechanism for feeding the stock which is adapted to carry it along beneath the nozzle in the manner indicated above, will now be described. A bracket 55 is provided with a cylindrical shank or pivot 57 which is held in a bore in the frame of the machine by means of a screw bolt 59. Rotatably mounted in bosses in this bracket is a shaft 61 which carries at one end a feed wheel 63 and at the other end a driving pulley 65. A spring 67 fastened at one end to the frame of the machine by a screw 69 and having at its opposite end engagement with a hole 71 tends to turn the bracket 55 and thereby to keep the feed wheel 63 raised, it being understood that the spring 67 is stronger than the spring 51 which acts upon the valve. Stops 73 and 75 threaded through bosses on the frame serve to limit adjustably the angular movement of the bracket 55; and the rod 77 pivotally attached to said bracket may be actuated by any suitable mechanism as, for example, by a treadle 79 to depress the feed wheel and permit a piece of stock to be fed to the machine. Fast to the cover 6 of the feed box 7 is an arm 81 having a bore 83 in which a sleeve 85 is held by means of a set screw 87, the stem 89 of the feed disk 91 being rotatable in said sleeve. A thumb nut 93 provided with a socket to receive a spring 95 is threaded into the upper end of the bore 83, a ball 97 being located between said spring and a head 99 provided on the upper end of the stem 89. The feed disk 91 engages a reduced portion 101 of the feed wheel 63 and serves in connection with this reduced portion to grip the stock and thereby insure its proper forward movement. An edge gage 103 of ordinary form is adjustably attached to the bracket 55 by means of a set screw 105.

The operation of the machine is as follows:—The stop 73 is adjusted in accordance with the thickness of the stock to be cemented, and power is applied in any suitable manner to the pulleys 17 and 65. The treadle 79 is then depressed and a piece of stock is fed to the machine with its edge in contact with the gage 103. As the stock is fed forward the valve 37 is opened and cement is squirted through the grooves 41 on to the surface of the stock; and as the

stock continues its forward movement the cement thus forcibly ejected upon it, is wiped into the stock by the member 39. The cement is thus effectively rubbed into the fibers and pores of the stock so that a satisfactory coating is obtained.

Although the invention has been set forth in connection with a machine for applying a coating of cement to leather, it should 10 be understood that the invention is not limited in the scope of its application to the particular machine shown and described.

Having described my invention, what I claim as new and desire to secure by Letters 15 Patent of the United States is:—

1. A machine of the class described having, in combination, a receptacle for cement, a nozzle connected therewith, said nozzle being provided at its delivery end 20 with a narrow elongated aperture of different cross-section from that of the bore of the nozzle, a valve seat being formed at the junction of said elongated aperture and said bore, a valve shaped to fit said seat, and a 25 wiper fast to said valve, said wiper corresponding in cross-section to the cross section of said elongated aperture, protruding from said aperture and being provided with a passage located at one side of the center 30 thereof.

2. A machine of the class described having, in combination, means for feeding forward a piece of stock, power actuated means for squirting cement upon said stock, and 35 a smooth-faced wiper having a rounded end arranged to contact with the stock close to the point of application of cement and adapted to rub the cement into the stock.

3. A machine of the class described having, in combination, a receptacle for cement, 40 a nozzle leading from said receptacle, said nozzle being provided with a valve seat, an imperforate valve coöperating with said seat, a wiper rigid with said valve and arranged to contact with the stock after the 45 cement has been delivered upon said stock, said wiper extending through the delivery opening of said nozzle, a spring normally holding said valve upon said seat, and means 50 for feeding a piece of stock past said nozzle.

4. A machine of the class described having, in combination, a receptacle for cement, a nozzle leading from said receptacle, said nozzle being provided with an elongated delivery opening, a wiper located in said opening, said wiper conforming in the outline of its cross-section to the outline of the opening and having formed in one side thereof a plurality of passages, an imperforate valve 55 for controlling the flow of cement through the nozzle and means for feeding a piece of stock past said nozzle and for pressing it against said wiper during the feeding movement.

5. A machine of the class described having, in combination, a receptacle for cement, 65 said receptacle being provided with an outlet, a deflector adjacent said outlet, means acting solely through friction with the cement in conjunction with the deflector for 70 causing said cement to accumulate under pressure at said outlet whereby said outlet may be kept closed while the operation of the means acting through friction continues, and means for controlling the flow of 75 cement through said outlet.

6. A machine of the class described having, in combination, a receptacle for cement, 80 said receptacle being provided with an outlet, a deflector adjacent said outlet, means for controlling the flow of cement through said outlet, a rotary device located in said receptacle and acting solely through friction in conjunction with said deflector to direct the cement toward said outlet, the surface of 85 said device which is exposed to the cement being of greater extent than that of the interior of the receptacle.

7. A machine of the class described having, in combination, a receptacle for cement, 90 said receptacle being provided with an outlet, a plurality of thin members spaced apart located in said receptacle, means for rotating said members whereby a force is frictionally exerted upon the cement which 95 tends to move said cement in the direction of rotation of said members, means for deflecting the cement toward the outlet, and means for controlling the flow of cement through said outlet.

8. A machine of the class described, having, in combination, a receptacle for cement, a nozzle leading from said receptacle, means for feeding stock past said nozzle, a deflector and coöperating means acting through friction with the cement for supplying cement under pressure to the nozzle, and a combined 105 valve and wiper arranged to be moved by the stock to open the nozzle and to coöperate with the feeding means in wiping into the 110 pores of the stock the cement delivered through the nozzle.

9. A machine of the class described having, in combination, a cylindrical receptacle 115 for cement, a plurality of spaced disks rotatably mounted in said receptacle, means for rotating said disks, a deflector arranged to coöperate with said disks in applying pressure to the cement, a nozzle leading from said receptacle, a combined valve and wiper 120 carried by said nozzle, a feed wheel, an angularly movable bracket by which said wheel is carried, a spring normally holding said bracket in raised position, means for lowering said bracket, and means for rotating said feed wheel.

10. A machine of the class described having, in combination, a cylindrical receptacle

for cement, a plurality of spaced disks mounted in said receptacle, means for rotating said disks, a deflector arranged to co-operate with said disks, a cement applying member, and means for conducting cement from said receptacle to said member.

In testimony whereof I have signed my

name to this specification in the presence of two subscribing witnesses.

LOUIS W. G. FLYNT.

FRED C. PATRICK.**

Correction in Letters Patent No. 1,163,651.

It is hereby certified that in Letters Patent No. 1,163,651, granted December 14, 1915, upon the application of Louis W. G. Flynt, of Rochester, New York, for an improvement in "Cementing-Machines," an error appears in the printed specification requiring correction as follows: Page 2, line 56, for the words "cross piece 49 carried by" read *fit snugly in the bore of*; and that the said Letters Patent should be read with this correction therein that the same may conform to the record of the case in the Patent Office.

Signed and sealed this 18th day of April, A. D., 1916.

[SEAL.]

R. F. WHITEHEAD,

Acting Commissioner of Patents.
